UNITED STATES PATENT OFFICE

155,297

DESIGN FOR A MINIATURE JEWELRY
SCREW DRIVER

Julian Harold Kushner, New York, N. Y.

Application May 20, 1948, Serial No. 146,500

Term of patent 14 years

(Cl. D45—1)

To all whom it may concern:

Be it known that I, Julian Harold Kushner, a citizen of the United States, residing in the city of New York, State of New York, have invented a new, original, and ornamental Design for Miniature Jewelry Screw Driver, of which the following is a specification, reference being had to the accompanying drawing, forming part thereof.

Fig. 1 is a perspective view of a miniature jewelry screw driver, showing my new design.

Fig. 2 is a side elevational view thereof.

Fig. 3 is an elevational bottom view of my new design.

Fig. 4 is a front elevational view.

Fig. 5 is a rear elevational view thereof.

The essential features of my design reside in the two heart-shaped figures which merge in an area coaxially with the shank whereby the V-formation of each heart-shaped figure is laterally spaced from the second figure, the lower ends of

the figures merging into a solid wall of connection.

I claim:

The ornamental design for a miniature jewelry screw driver, as shown.

J. HAROLD KUSHNER.
